US0D1099091S

(12) **United States Design Patent** (10) **Patent No.:** **US D1,099,091 S**
(45) **Date of Patent:** **** Oct. 21, 2025**

(54) **PORTABLE COMPUTER**

(71) Applicant: **Lenovo (Beijing) Limited**, Beijing (CN)

(72) Inventor: **Peiyin Yang**, Beijing (CN)

(73) Assignee: **Lenovo (Beijing) Limited**, Beijing (CN)

(**) Term: **15 Years**

(21) Appl. No.: **35/519,546**

(22) Filed: **Dec. 1, 2023**

(80) **Hague Agreement Data**

Int. Filing Date: **Dec. 1, 2023**

Int. Reg. No.: **DM/233971**

Int. Reg. Date: **Dec. 1, 2023**

Int. Reg. Pub. Date: **Dec. 29, 2023**

(30) **Foreign Application Priority Data**

Jun. 14, 2023 (CN) 202330365899.7

(51) **LOC (15) Cl.** **14-02**

(52) **U.S. Cl.**

USPC **D14/315**

(58) **Field of Classification Search**

USPC D14/315-323, 326-327, 371, 374, D14/432-434, 439; D8/306, 323, 325, D8/329

Assistant Examiner — Altaira J Swangin

(74) *Attorney, Agent, or Firm* — SYNCODA LLC; Feng Ma

(57) **CLAIM**

The ornamental design for a portable computer as shown and described.

DESCRIPTION

1.1 Front view

1.2 Back view

1.3 Left view

1.4 Right view

1.5 Top view

1.6 Bottom view

1.7 Top perspective view in a closed state

1.8 Perspective view in a state of use

1.9 Perspective view in another state of use, showing the display panel and hinge component separated from the keyboard panel

1.10 Front view

1.11 Back view

1.12 Left view

1.13 Right view

1.14 Top view

1.15 Bottom view

1.16 Perspective view

(Continued)

1.17 Front view in another state of use, showing the keyboard panel component separated from the display panel and hinge

1.18 Back view

1.19 Left view

1.20 Right view

1.21 Top view

1.22 Bottom view

1.23 Top perspective view

The broken lines shown in the drawings illustrate portions of the portable computer and form no part of the claimed design.

1 Claim, 14 Drawing Sheets
